Patented Nov. 20, 1928.

UNITED STATES PATENT OFFICE.

FRANCIS W. CARPENTER, OF MINNEAPOLIS, MINNESOTA, ASSIGNOR OF ONE-HALF TO
MAURICE H. GRAHAM, OF ST. LOUIS PARK, MINNESOTA.

CIGARETTE CASE.

Application filed May 9, 1927. Serial No. 189,867.

My present invention has for its object to provide an extremely simple and highly efficient cigarette case designed to hold, at one time, all of the cigarettes from a complete standard package in such a manner that the cigarettes cannot get out of position, and wherein their movements may be controlled and the cigarettes positioned for discharge from the case without binding or injury.

10 To the above end, generally stated, the invention consists of the novel devices and combinations of devices hereinafter described and defined in the claims.

In the accompanying drawings, which illustrate the invention, like characters indicate like parts throughout the several views.

Referring to the drawings:
Fig. 1 is a top view of the cigarette case with a portion thereof broken away to show 20 the cigarettes therein;

Fig. 2 is a side elevation of the same;
Fig. 3 is a transverse section taken on the line 3—3 of Fig. 1, with some parts shown in different positions by means of broken lines;
Fig. 4 is a detail view in longitudinal sec-

25 Fig. 4 is a detail view in longitudinal section taken on the line 4—4 of Fig. 3;
Fig. 5 is a horizontal section taken on the line 5—5 of Fig. 3, with some parts broken away and other parts shown in different positions by means of broken lines, and also showing a cigarette partly ejected from the case.

Fig. 6 is a horizontal section taken on the line 6-6 of Fig. 3 with some parts shown in different positions by means of broken lines; and

Fig. 7 is a fragmentary detail view in section taken on the line 7—7 of Fig. 5, on an enlarged scale.

The cigarette case comprises a box-like body 8 having a cover 9 connected thereto by a hinge which extends the full length of said case, projects into the body thereof, and affords a medial supporting ledge 10, for a purpose that will presently appear. Said cover 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 A liner 12 is provided for the body 8 and is held in place by frictional engagement with the inset portion of said body, and is spaced from said body below the inset portion there-

of. The upper edge portions of the front and sides of the liner 12 are turned laterally outward, rest on the underlying upper edges of the body 8, and support said liner spaced from the bottom of the body 8.

An aligning channel 13 is formed at the rear of the body 8 under the supporting ledge 10, and is of such size, in cross section, as to hold a cigarette α with freedom for endwise sliding movement. This channel 13 is formed by the bottom of the body 8, the rear wall of said body and the rear portion of the bottom of the liner 12, which terminates short of said body. It will be noted that the sides of the liner 12 have openings 14 to expose the sides of the body 8. A discharge passage 15 is formed in one side of the body 8 in alignment with the channel 13 and of such size as to permit a cigarette α to be projected endwise therethrough, as shown in Fig. 5. 70 75

It will be noted that the length of the liner 12 is slightly greater than that of the cigarette x , but that the width thereof is materially greater than the length of the cigarettes. To prevent the cigarette x from turning endwise in the liner 12, there is provided a partition 16 which divides said liner into a supply compartment 17 at the rear of the case and a reserve compartment 18 at the front of the case.

The end portions of the partition 16 are bent laterally into the reserve compartment 18 to afford ears 19 pivoted at 20 to the sides of the liner 12 and hold said partition with freedom for raising and lowering movements in said liner. The longitudinal edge portions of the partition 16 are curved rearwardly, as best shown in Fig. 3, to eliminate sharp edges on said partition which might damage the cigarettes in the case when the partition 16 is moved into the liner 12. 95

By reference to Fig. 5 it will be noted that the length of the supply compartment 17 is materially less than the width thereof so that the cigarettes in said compartment cannot turn endwise, and by tilting the cigarette case the cigarettes may be caused to roll to the rear of the case and one thereof will always enter the aligning channel 13 and be positioned thereby to be projected through the discharge passage 15. By reference to Fig. 3 it will be noted that the case is completely filled with cigarettes and that there are two tiers thereof. The cigarette, at the rear of the case in the upper tier is held by the supporting ledge 10

out of contact with the cigarette in the aligning channel 13 so as not to interfere with the free projecting movement thereof in said aligning trough.

- 5 A sliding gate 21 is mounted to slide on the same side of the body 8 as the discharge passage 15 and has a laterally projecting flange 22 slidably mounted on the bottom of said body. The gate 21 is operated in one direction 10 to close the discharge passage 15 by a spring 23 anchored to a post 24, on the bottom of the body 8, and attached to the flange 22. To open the gate 21 against the tension of the spring 23, there is attached thereto a button 15 25 which projects outward of the casing and has a reduced neck which works in a slot 26 in the body 8. This button 25 holds the gate 21 in position for straight-line sliding movement.
- 29 Ejector mechanism actuated by the gate 21 is provided for moving the cigarette endwise in the aligned channel 13 and part way through the discharge passage 15 where the same may be removed from the case, as shown 25 in Fig. 5. This ejector mechanism includes a bell-crank lever 27 pivoted to the post 24 and having its short arm attached to the flange 22 by a slip joint comprising a hook-like pivot lug 28 on said arm which works in a longitudinal slot 29 in said flange. An arm 30, in the form of a rod, is pivoted to the long arm of the lever 27 and has its free end bent laterally to form a finger 31. This finger 31 extends transversely of the aligning channel 13 and has an annular end portion axially aligned 35 with the discharge passage 15 and adapted to engage the inner end of a cigarette, as indicated in Figs. 5 and 7. The flange 22 slides directly on the bottom of the body 8 and has 40 raised portions under which the spring 23 and the short arm of the lever 27 project. A finger 32 on the lever 27 overlies the arm 30 and holds the same in pivotal connection with said lever. The gate 21 and the ejector mechanism are mounted between the body 8 and the liner 12 and thereby do not interfere with the cigarettes in the case.

50 As previously stated, the gate 21 is yieldingly held by the spring 23 and normally closes the discharge passage 15, and the ejector mechanism is held by the flange 22 in a position in which the finger 31 engages the opposite side of the body 8 from the discharge passage 15, and the liner 12 projects outward thereof so that said finger will not interfere with the lateral movement of the cigarettes in the case as they are positioned in the aligning channel 13. The arm 30 works through a guide slot 33 in the liner 12 and holds the finger properly positioned in respect to the aligning channel 13 for engagement with a cigarette therein.

55 The slip connection 28-29 between the gate and ejector mechanism is so arranged 60 that the gate 21 is moved, by pressure ap-

plied to the button 25, completely out of the field of the discharge passage 15 before it starts to operate the ejector mechanism to move the cigarettes in the aligning channel 13 and through said discharge passage. After a cigarette has been removed from the case, the button 25 is released and the spring 23, which has been placed under tension by the opening of the gate 21, returns said gate to its closed position and also resets the ejector mechanism during the final closing movement of said gate.

65 As previously stated, the supply compartment 17 and reserve compartment 18 will hold all of the cigarettes removed from a complete package and when the supply in the compartment 17 has been exhausted, the partition 16 may be raised to allow the cigarettes in the reserve compartment 18 to roll into the supply compartment 17.

70 The supporting ledge 10 will hold the adjacent cigarette in the upper tier from dropping down on the cigarette in the aligning channel 13 and thereby interfering with the ejecting movement of the cigarettes in said aligning channel 13.

75 The liner 12 prevents loose tobacco from interfering with the movable parts in the cigarette case, and the gate 21 not only prevents the cigarettes from accidentally working out of the case, but it prevents the escape of loose tobacco from the case.

80 By reference to Fig. 5 it will be noted that the liner 12, at its opening 14, adjacent to the discharge passage 15, is substantially 100 funnel-shaped and concentric to said passage to assist in directing a cigarette there-through.

85 To further secure the liner 12 to the body 8 in addition to the frictional engagement therebetween, a plurality of holes are punched in the liner 12 and the body 8 is upset therein to afford separable connections 34 which detachably secure said liner to the body 8.

90 What I claim is:

1. In a cigarette case, a body having a displaceable cover, and a partition in the body dividing the same into a supply compartment and a reserve compartment, said supply compartment having a discharge passage and being of a width less than that of the length thereof, said partition being displaceable to permit cigarettes to be moved laterally thereunder from the reserve compartment to the supply compartment.

95 2. The structure defined in claim 1 in which the partition has laterally projecting ears pivoted in respect to the body.

100 3. In a cigarette case, a body having a displaceable cover, said case being of such depth as to hold two tiers of cigarettes, said case having an aligning channel and a discharge passage at one end thereof, and a fixed supporting ledge on the case above the

aligning channel for holding an overlying cigarette out of contact with a cigarette in said channel.

4. In a cigarette case, a body, a cover, and a hinge connecting the cover to the body, said case being of such depth as to hold two tiers of cigarettes, said body having an aligning channel and a discharge passage at one end thereof, said hinge extending into the body above the aligning channel and affording a supporting ledge for holding an overlying cigarette out of contact with a cigarette in said channel.

5. In a cigarette case, ejector mechanism comprising a bell-crank lever, an ejector member having one of its ends pivoted to one arm of said lever and having a follower

on its other end, a sliding gate, a slip connection between the gate and the other arm of said lever, a guide for causing the follower of the ejector member to move in a predetermined path, and a spring for actuating the ejector mechanism in one direction.

6. A cigarette case having a discharge passage, a gate normally closing said passage, ejector mechanism connected to the gate whereby said mechanism will be operated when the gate is moved, and a loose connection between said gate and mechanism to permit the gate to open in advance of the ejecting action of said mechanism.

In testimony whereof I affix my signature.
FRANCIS W. CARPENTER.
